Specification of Letters Patent. Patented Aug. 12, 1913.

Application filed January 25, 1910. Serial No. 539,942.

To all whom it may concern:

Be it known that I, HENRY B. COOLEY, a citizen of the United States, and resident of New Britain, in the county of Hartford and State of Connecticut, have invented a new and useful Flat-Bed Rotary Printing-Press, of which the following is a specification.

My invention relates to a flat bed rotary printing press with the object in view of providing a press of this character which will perform its work in a rapid and efficient manner.

A practical embodiment of my invention is represented in the accompanying drawings in which,

Figure 1 is a view of the press in rear elevation; Fig. 2 is a view in end elevation; Fig. 3 is a vertical central section from front to rear; Fig. 4 is a vertical section in the plane of the line A—A, Fig. 1; Fig. 5 is a detail elevation partly in section, showing the mechanism for preventing the impression cylinder from engaging the type on the form cylinder when no paper is fed; Fig. 6 is a view in detail showing the means for locating the cam shaft in its timed position when the gear is changed; Fig. 7 is a view in detail showing the arrangement of the contact plates for maintaining the electric circuit closed to prevent the impression cylinder from smutting when it is not carrying paper to be printed. Fig. 8 is an enlarged top plan view of the impression cylinder and its accessories. Fig. 9 is a view of the same in end elevation. Fig. 10 is a transverse section of the same in the plane of the line B—B of Fig. 8. Fig. 11 is a similar section taken in the plane of the line C—C of Fig. 8. Fig. 12 is a partial longitudinal central section through the same. Fig. 13 is a view in detail showing the crank arm on the gripper shaft and its engagement with the stationary cam for positively opening the grippers. Fig. 14 is a view in detail showing the arm on the gripper shaft and its actuating spring for closing the grippers, and Fig. 15 is a view in detail showing the vibrating arm which supports the electromagnet for controlling the position of the impression cylinder with relation to the form cylinder and the cam for operating the arm.

My invention contemplates continuously

rotating form and impression cylinders, the form cylinder being provided with one or more flat beds, in the present instance, two, for receiving the type chases and the impression cylinder being provided with curved paper receiving faces arranged to coact with the type on the flat beds of the form cylinder, the speed of rotation being so regulated that there will be a retarded movement of the form and impression cylinders during the actual contact of the paper to be printed with the type and an accelerated movement of the cylinders intermediate of two consecutive printing operations.

My invention further contemplates one or a plurality of printing operations during each revolution of the impression cylinder and the automatic shifting of the impression cylinder bodily away from the form cylinder whenever a paper carrying face on the impression cylinder fails to receive paper to be printed.

My invention further contemplates means for adjusting the paper carrying faces of the impression cylinder both radially and rotatively and various other features of construction and combinations of parts as will be hereinafter particularly described.

The frame of the machine is denoted by 1. It is made sufficiently strong and heavy and of such form as to conveniently support the several parts in such a manner as to prevent undue vibration. The drive shaft, denoted by 2, is provided with fast and loose pulleys 3 and 4 which receive power from a suitable source, not shown. The drive shaft 2 also carries a balance wheel 5.

The shaft on which the form cylinder is carried is denoted by 6. It is suitably mounted in the frame 1 and receives a rotary movement directly from the drive shaft 2, through the pinion 7 on the drive shaft and the spur wheel 8 on the form cylinder shaft 6. The form cylinder is provided with two oppositely disposed flat faces 9 and 10 for receiving the type chases 11 and 12, and with two oppositely disposed curved faces 13 and 14. At one end the shaft 6 carries two mutilated gear wheels or disks arranged side by side operating as complements of each other. One of these gears is on a circular disk 15 and

the other on a disk 16 having two flat sides and two rounded sides corresponding to a cross section of the form cylinder hereinabove described. The disk 15 is provided with spur teeth along those portions of its periphery which correspond to the curved faces of the disk 16 and is left smooth rimmed intermediate of these portions and the disk 16 is provided with spur teeth along its flat sides and left smooth rimmed intermediate of these portions. These mutilated spur gears drive the impression cylinder as will later appear.

The impression cylinder consists of two semi-cylindrical segments denoted by 17, 18, each mounted in rotative and radial adjustment and carried bodily by end frames 19 fixed to rotate with a shaft 20, the latter mounted in eccentric bearings in the frame 1 for purposes which will hereinafter more particularly appear. The segments 17, 18, are here shown arranged diametrically opposite each other with respect to the shaft 20, and their relation to the form cylinder is such that they will normally travel along the flat beds of the form cylinder with their curved surfaces sufficiently close to the said flat beds to press the paper carried by them into printing contact with the type held on said flat beds. As the two printing segments of the impression cylinder are alike in their structure and operation, a description of one will suffice for both. Referring to the segment 18, Figs. 10, 11 and 14, a blanket 21, in the present instance a paper blanket, leads from retaining rolls 22 at one edge of the segment over the face of the segment to a rocking clamp 23 at the opposite edge, the clamp being adjusted by a screw 24 engaged with the tail of the clamp and pressing against the axle 25 of the segment. Grippers, like the gripper 26, are fixed on a rock shaft 27 carried by the segment and are operated at the proper intervals to grip the edge of the paper, fed onto the segment, by a spring 28 attached to an arm 29 on the shaft 27 and to a pin 30 on the hub of the end frame of the impression cylinder. An abutment 31, one for each gripper, for engaging the advance edge of the paper and squaring it on the printing segment, is loosely mounted on the shaft 27 with a pin 31* extending laterally through an elongated slot 32 in the gripper 26, the tail of the stop being acted on by a spring 32* tending to force the operating end of the abutment toward the face of the segment when the rocking movement of the gripper will permit it to do so. A fixed cam 33 engages an arm 33* on the rock shaft 27 to open the gripper and with it the abutment, the said cam being provided with an intermediate ledge 34 to permit the partial rotation of the shaft 27, sufficient to allow the abutment to fall under the in-

fluence of its actuating spring into operative position on the segment in advance of the complete movement of the gripper into its operative position.

In practice, when a sheet is about to be fed onto the segment, the gripper will be rocked sufficiently to allow the abutment to take its position to arrest the sheet and the gripper will then after the sheet has reached its position close down onto it and hold it during the printing operation. The slot 32 permits this motion of the gripper independently of the movement of the abutment. The segment 18 is provided with a hub 35 at each of its ends and these hubs are received in recesses 36 in sliding bearings 37 in the frames 19, which bearings also receive the axle 25. Set screws 38 extending through elongated slots 38* in the upper portion of the said sliding bearings and into the segment, serve to hold the segment in the desired rotary adjustment about the axis of the axle 25, while screws 39 tapped into the hubs of the frames 19 and provided with lock nuts 40, serve to hold the said segments in the desired radial adjustment.

The radially adjustable bearings 37 for the impression segments have rims 37* which are just blanket high and which bear on shoes 11* on the form cylinder, the latter just type high. The rims contact with the shoes just prior to the engagement of the type with the sheet and continue to bear until the type leave the sheet, thereby preventing slurring of the imprint.

The impression cylinder shaft 20 carries on one end mutilated gearing consisting of a wheel 41 provided on its periphery with spur teeth sections 42, 43, arranged diametrically opposite each other, the spaces intermediate of the adjacent ends of said spur toothed sections being bridged by semi-circular sections of spur teeth 44 and 45, on arcs of lesser radius than the radius of the arcs of the sections 42, 43, and located laterally out of the plane of the sections 42, 43. The radius of the toothed sections 42, 43, is less than the radius of the tooth sections of the disk 15 hereinbefore described, while the number of teeth on each of the sections 42 and 43 corresponds to the number of teeth on each of the toothed sections of the disk 15. In like manner the number of teeth on each of the toothed sections 44, 45, correspond to the number of teeth on each of the flat sides of the disk 16. The disk 15 and wheel 41 are in the same plane and so arranged that the teeth on disk 15 will engage the teeth on the wheel 41 and the disk 16 and toothed sections 44, 45 are in the same plane and so arranged that the teeth on the flat sides of the disk 16 will engage the teeth on the sections 44, 45. The structure and arrangement of the inter-operating gear sections is such, moreover, that

5 a tooth on the flat section of the disk 16 will engage a tooth on the section 44 or 45 before the teeth of the curved toothed section on the disk 15 leave the teeth on the section 42 or 43. The smooth rim portions of the 10 inter-engaging gear on the disks 15, 16, and wheel 41 are located in the pitch lines of the gear sections laterally adjacent thereto and inter-engage to form bearers for the form and impression cylinders to direct the 15 teeth of the engaging gears into engagement without any cramping or grinding. The toothed sections 44, 45, correspond to the positions of the printing segments of the impression cylinder and the sections 42, 43, 20 to the intervals between the printing segments and because the teeth on a toothed section of the wheel 41 extend along a greater proportion of the periphery of the 25 wheel than the curved toothed section on the disk 15 extends, due to the number of teeth on the said sections being the same and the radius of the section 42 or 43 less than the radius of the section on the disk 30 15, the wheel 41 and hence the impression cylinder will rotate faster than the disk 15 and hence faster than the form cylinder, during the interval between two printing operations. Again, because the teeth on the 35 flat side of the disk 16 correspond in number to the teeth on the sections 44 or 45 and occupy a chord of an arc on the disk 16 greater than the arc bridged by the section 44 or 45 on the wheel 41, the wheel 41 and hence the impression cylinder will rotate slower than the disk 16 and hence slower than the form cylinder during the printing operation.

40 It is to be noted that where a plurality of impression segments are provided as above described, the paper may be fed onto one impression segment while another is printing and hence while the impression cylinder is moving at a reduced speed; and as the speed 45 of the feed rollers, hereinafter referred to, is uniform, there is a reduction of speed of the impression cylinder relative to the feed at the time the sheet is being fed onto the impression segment and hence the sheet fed 50 is caused to positively register against the abutments 31. This variation in the relative speeds of the feed rollers and impression cylinder is accentuated so far as it affects the registering of the sheet by the fact that the abutments 31 are located nearer the axis of the impression cylinder than the curved surfaces of the impression segments and, hence travel slower than said surfaces as the impression cylinder rotates.

55 *Anti-smutting mechanism.*—To prevent the face of an impression segment of the impression cylinder from engaging the face of the type on the form cylinder when either from intention any impression segment is 60 not provided with a sheet to be printed, or,

unintentionally a sheet fails to be fed in position, the shaft of the impression cylinder and hence the impression cylinder itself is automatically moved bodily away from the face of the type and held away during the 70 time the face of the impression segment is traveling over the face of the type. This is accomplished as follows. The impression cylinder shaft 20 is mounted eccentrically in bearings one of which is shown at 46, (Fig. 75 5), it being understood that a similar bearing is provided for the shaft 20 at the opposite side of the frame. The bearing 46 and its companion are in turn rotatably mounted in suitable bearings in the supporting 80 frame. Pitmen 47 and 48 are jointed respectively to split collars 49 clamped on the bearing 46 and its companion, the said pitmen being engaged at their opposite ends by cams 51, 52, on the cam shaft 53, the latter 85 being driven from the drive shaft 2 through the gears 151, 152 on the drive shaft and gears 149, 150 on the cam shaft, (see Fig. 6). A spring 56 tends to draw the rollers 57, 58, on the pitmen into engagement with the cams 51, 52, lowering the pitmen and hence rocking the bearing 46 and its companion and thereby moving the shaft 20 sufficiently to prevent the face of an impression segment from touching the face of 90 the type. The pitmen 47, 48, are held from unintentional dropping by stop blocks 59, 95 adjustably attached to the pitmen by means, for example, of an elongated slot and set screw 61, 62, which stop blocks rest on a 100 shoulder 63 on a slide 64 supported in a way 65 secured to the frame, the slide being provided with a pin 66 against which the end of a slide operating arm 68 bears. It 105 is to be understood that there are two slides similarly constructed and arranged, one for each stop block, and that there are two slide operating arms connected by a bottom element 69, forming a general U-shaped structure pivotally secured to the outer sides of 110 the frame 1, one of the pivots being shown at 70. The element 69 is provided with an armature 71 which co-operates with an electromagnet 72 carried by the lower end of a 115 vibrating arm 73 pivoted to the frame at 74 and connected by a pitman 75 with the shaft 53 on which the forked end of the pitman rides. The pitman 75 is provided with a roller 76 in position to engage a cam 77 similar to the cam 51, to rock the arm 73 against the tension of its retracting spring 78. The slides are moved by springs, one 54 being shown in Fig. 5, into position to arrest the stop block 59 and its companion, thereby 120 holding the pitmen 47, 48, suspended and the impression cylinder in printing position. The parts will remain in this position so long as the electromagnet 72 remains de- 125 energized, the latter swinging back and forth as the arm 73 is swung during the revolution 130

tion of the shaft 53, without effect upon the element 69 and its arms. When, however, the electromagnet 72 is energized, it will attract the armature 71 and hence cause the element 69 and its arms to swing in a direction to move the slides against the tension of the spring 54 and its companion, thereby dislodging the stop blocks from the slides, allowing the pitmen 47, 48, to drop and thereby throw the impression cylinder out of touch with the type. The energizing and deenergizing of the electromagnet 72 is accomplished as follows: An electric circuit is formed by wires 79, 80, leading from the opposite poles of a battery 81 to binding posts 82, 83, on a projection of the frame 1. Curved contact strips 84, 85, are carried by an end frame of the impression cylinder, a pair of these strips for each impression section of the cylinder, in position to contact respectively with the binding posts 82, 83, during the time the face of the impression section is passing along over the type. These contact strips or plates are connected with contact terminals 86, 87, exposed on the face of the impression section and at all other points suitable insulated from the cylinder. The construction here shown is insulated wires 88, 89, leading from the strips 84, 85, through rubber plugs 90, 91, set in the cylinder. A bridge piece 92 of suitable conducting material, as, for example, brass, is pivoted to a bracket 93 secured to and insulated from the advance edge of the impression section in position for the branches of its forked end to swing into and out of contact with the terminals 86, 87, at the face of the impression section. A spring 94 tends to hold the bridge piece out of contact with the terminals.

The bridge piece is forced into contact with the terminals to complete the electric circuit through the strips 84, 85, and binding posts 82, 83, by a dog 95 consisting in the present instance of a flat piece of steel having its end split to form branches 96, 97, and secured to an arm 98 attached to an insulating block 99, fixed on a rock shaft 100 mounted in the end frames of the cylinder and provided at one end with a crank 101, the pin on which is provided with a roller in position to engage a cam 102 fixed to the frame 1 and shaped as to rock the dog 95 and hold it out of position to press the bridge piece 92 into contact with the terminals 86, 87, during the interval when the impression segment is traveling intermediate of successive forms of type on the form cylinder; but permitting the dog 95 to be rocked by its actuating spring 103 attached to an arm 104 on its shaft, during the period when the impression segment is moving over the type on the form cylinder, in a direction to press the branches of the bridge piece into contact with the terminals 86, 87, there-

by completing the circuit through the electromagnet 72 and causing the shaft of the impression cylinder and hence the impression cylinder to be moved during such period away from the face of the type. The split end of the dog 95 insures the pressure of the branches of the bridge piece into close contact with their respective terminals.

The location of the terminals and the bridge piece is such that when a sheet of paper is fed into position on an impression segment, it will cover the terminals 86, 87, before the bridge piece is pressed down toward them and hence will insulate them from the bridge piece so that the electromagnet 72 will not be energized excepting when no sheet is supplied to the impression section. Hence, so long as the sheets are fed properly to the impression sections, the impression cylinder will remain in position to engage the type but whenever an impression cylinder fails to receive a sheet that impression section will not engage the type and hence its blanket will not become daubed or smutted.

The relation of the driving and driven gear is such that the rocking of the bearings carrying the impression cylinder shaft may take place, if permitted to rock, just before an impression section begins its travel over a type form and the cams 51 and 77 on the cam shaft serve to operate the respective pitmen 47 and 75 into position, the one to receive the stop blocks on the slides and the other to move the slides under the stop blocks.

Feed mechanism.—The feed mechanism which I prefer to employ is of the type shown, described and claimed in my Patent No. 874943 granted December 31st, 1907, and in my pending applications Serial No. 469249, feeding device, filed December 26, 1908, and Serial No. 469274, pneumatic pump, filed December 26, 1908, in which the sheets or articles to be printed are arranged in a pile 105 on a slanting table 106 and are drawn onto a feed roller 107 by suction and thence advanced by feed rollers to the impression cylinder. As in the patent referred to, the feed mechanism is operated by the cam shaft through jointed arms connected with a slide and the exhaust pump 108 is also operated from the cam shaft, the exhaust being communicated to the cylinder 107 through the tube 109. My present invention, however, provides for interrupting the suction and hence the feed when it is desired to use for the time being less than the whole number of impression segments, in the present instance, one instead of two such segments. To accomplish this, a cock 110 is inserted in the tube 109 and provided with an arm or crank 111, for opening and closing it. The crank 111 is connected by a link 112 with a vibrating arm 113 pivoted to

the frame at 114 and adapted to be operated by a pin 115 carried by a disk on the impression cylinder shaft in such position that it will engage and rock the arm 113 and thereby close the cock 110 and prevent suction just as one segment of the feed cylinder 107 approaches the position to draw a sheet onto it, thereby omitting the feed of a sheet. The link 112 is made readily removable so that whenever it is desired to feed a sheet to each impression section, the cock 110 may be disconnected from the arm 113 and the suction made thereby continuous.

15 It will be observed that there is an intimate co-active relation between the means for interrupting the suction and means for moving the impression cylinder away from the type form, since the latter movement 20 takes places when no sheet is fed and no sheet is fed when the suction is interrupted. The sheet received on the face of an impression segment is held smoothly thereon as the impression segment moves toward the 25 type form, by curved spring arms 116 suspended by a rod 117 in the path of the impression section.

Delivery mechanism.—The particular structure and operation of the delivery 30 mechanism forms the subject-matter of a separate application, Serial No. 539941 filed of even date herewith. It consists briefly stated, of two endless carriers composed of tapes 118 and 119, the former passing around 35 guide rollers 120 and 121 and in engagement with pulleys 122 on the cam shaft, by which the tapes are driven, and the latter passing around a roller 123 mounted in brackets on the frame and around a floating roller 124. 40 The roller 123 is driven by a band from a pulley on the cam shaft and the floating roller 124 is rocked by cranks 125 on the shaft of the roller 123, the said cranks being operated by pitmen 126, 127, connecting the 45 cranks with cams on the impression cylinder shaft. The floating roller 124 is lifted and lowered at such intervals as to direct the printed sheets alternately into the receivers 128 and 129.

50 *Ink distributing mechanism.*—The ink distributing mechanism which I prefer to employ forms the subject-matter of a separate application Serial No. 539943 filed of even date herewith and is constructed to 55 thoroughly grind, spread and evenly apply the ink to the face of the type. The ink fountain is denoted by 130, the ink roller by 131, the doctor by 132, the rotary and longitudinally reciprocating ink distributing 60 drum by 133 and the rollers for transferring and applying the ink by 134, 135, 136 and 137, the two latter rollers being arranged to cooperate with a second ink distributing and smoothing drum 138.

65 In order that the cam shaft may be kept

in time during the shifting of gear to reduce or increase the speed of the cam shaft relatively to the speed of the drive shaft, as, for example, when it is desired to shift from printing with two impression segments to 70 printing with one impression segment or vice versa, a disk 139 is fixed on the cam shaft and provided with a recess 140 extending radially inward from its periphery. A longitudinally sliding bar 141 is mounted in 75 the frame and provided with a pin 142 of such size that it will pass through the recess 140 with an easy sliding fit when the bar 141 is advanced or returned. The bar 141 is also provided with a rack 143 engaged by 80 a toothed sector 144, the latter pivoted to the frame 1 and provided with an operating handle 145. The said bar 141 is further provided with a shifting arm 146 fixed thereon, its upper end being constructed to 85 enter a groove 147 on a sleeve 148 splined on the cam shaft and provided with gear wheels 149, 150, of different sizes and, for convenience, located on opposite sides of the groove 147. The gear wheels 149 and 150 90 are constructed to intermesh respectively with gear wheels 151 and 152 fixed on the drive shaft 2. When the gear 149 of lesser diameter and having a lesser number of teeth than the gear 150, is in mesh with the 95 gear 151 of greater diameter and having a greater number of teeth than the gear 152, the cam shaft will be driven at an increased rate of speed, to wit: a speed which will provide for printing with both the impression 100 segments, and when the gear 150 is in mesh with the gear 152, the cam shaft will be driven at a rate suitable for printing with one impression segment. The throw of the bar 141 to slide the gears 149 and 150 along 105 the cam shaft to bring either of the above intermeshing sets of gears into mesh with each other is sufficient to cause the pin 142 on the bar 141 to pass through the recess 140 in the disk 139 from one side of the disk to the 110 opposite side and hence the shifting of the gears can only take place when the recess 140 is in alignment with the pin 142, that is, when the cam shaft is in its properly timed 115 relation to the parts which co-act therewith.

The operation of the several parts of the machine have been so fully set forth with respect to the parts which co-act therewith that a detailed description of the operation as a whole is omitted as uncalled for.

120 In general it may be stated that the machine provides for expeditious and accurate work when the plurality of impression segments are in use and at the same time provides for the use of but one of the impression 125 segments without harm to an impression segment not in use.

It is evident that changes might be resorted to in the form and arrangement of the parts without departing from the spirit 130

and scope of my invention, hence I do not wish to limit myself strictly to the structure shown and described, but

What I claim is:

5. In a printing press; a form cylinder provided with a flat bed for receiving the type chase, means for continuously driving it, an impression cylinder provided with a curved impression segment for receiving the sheet to be printed and inter-coacting gears carried by the shafts of the form and impression cylinders, said gears including a straight line gear corresponding to the flat bed on the form cylinder, a curved gear corresponding to the impression segment on the impression cylinder and adapted to engage the straight line gear during the printing operation and gears carried respectively by the form cylinder shaft and impression cylinder shaft and located out of the plane of the aforesaid gears and arranged to intermesh intermediate of successive printing operations. 70
10. In a printing press; a form cylinder provided with a flat bed for receiving the type chase, means for continuously rotating it, an impression cylinder provided with a curved impression segment for receiving the sheet to be printed, and intercoacting gears carried by the shafts of the form and impression cylinders, said gears including a straight line or rack gear corresponding to the flat bed on the form cylinder, a curved gear corresponding to the impression segment on the impression cylinder and adapted to engage the straight line or rack gear during the printing operation, and intermeshing mutilated circular gears located at the side of and out of the plane of the aforesaid rack and curved gears, the said rack gear occupying a position corresponding to the chord of an arc on the mutilated circular gear greater than the chord of the arc occupied by the curved gear adjacent to the other mutilated circular gear, the said mutilated circular gear being arranged to intermesh alternately with the mesh of the rack and curved gears. 75
15. In a printing press, a form cylinder, an impression cylinder provided with a sheet registering abutment located nearer the axis of the impression cylinder than the impression surface of the cylinder, a paper feeding mechanism and means for reducing the speed of the impression cylinder relatively to the speed of the paper feeding mechanism at the time the paper is fed to the impression cylinder. 80
20. In a printing press, a form cylinder provided with a plurality of type receiving portions, an impression cylinder provided with a plurality of impression segments, and means for adjusting the impression segments independently of one another radially with respect to the axis of the impression cylinder and rotatively with respect to the axes of the impression segments. 85
25. In a printing press, the form cylinder provided with a plurality of type receiving beds, an impression cylinder provided with a plurality of impression segments, means for moving the impression cylinder bodily toward and away from the type receiving beds on the form cylinder, an air suction feed for feeding the sheets to the impression segments and means for interrupting the suction at predetermined intervals simultaneously with the bodily movement of the impression cylinder away from a type receiving bed on the form cylinder. 90
30. In a printing press, a form cylinder provided with a plurality of type receiving beds, an impression cylinder provided with a plurality of impression segments, an air suction feed for feeding the sheets on to the impression segments and a pin carried by the impression cylinder shaft for interrupting the suction at predetermined intervals to prevent the feeding of a sheet. 95
35. In a printing press, the combination with the drive shaft, and cam shaft, of different sets of intermeshing gears carried by the two shafts, a disk fixed on the cam shaft and provided with a recess extending inwardly from its periphery and a sliding bar connected with the gears on the cam shaft for shifting them and provided with a pin arranged to pass through the recess in the said disk, the arrangement of parts being such that the gear can be shifted only when the pin is in alignment with the said recess. 100
40. In a printing press, the combination with the drive and cam shafts and different sets of gears carried thereby in position to intermesh, the gears on the cam shaft being arranged to slide thereon, of a longitudinally sliding bar provided with a rack and carrying a pin and an arm for sliding the gears, a toothed segment provided with a handle for operating the bar and a disk fixed to the cam shaft and provided with a recess extending inwardly from its periphery through which the said pin on the bar may pass when the pin and recess are in alignment the said disk forming an obstruction to the movement of the bar when the said recess and pin are not in alignment. 105
45. In a printing press, the combination with the impression cylinder provided with radially adjustable impression segments 110
50. In a printing press, a form cylinder, an impression cylinder provided with an impression segment rotatably adjustable about an axis independent of the impression cylinder axis for carrying a sheet to be printed into engagement with the type and means for adjusting the 115
55. In a printing press, the combination with the impression cylinder provided with radially adjustable impression segments 120
60. In a printing press, a form cylinder for receiving the type, an impression cylinder provided with an impression segment rotatably adjustable about an axis independent of the impression cylinder axis for carrying a sheet to be printed into engagement with the type and means for adjusting the 125
65. In a printing press, the combination with the impression cylinder provided with radially adjustable impression segments 130

having bearing rims blanket high on the ends of the impression segments, of a form cylinder provided with shoes in position to engage the bearing rims on the impression segments, the arrangement of the parts being such that the bearing rims engage the shoes just before the type engage the sheet.

5 In testimony, that I claim the foregoing

as my invention, I have signed my name in presence of two witnesses, this 21st day of 10.
January 1910.

HENRY B. COOLEY.

Witnesses:

HENRY C. THIEME,
C. L. LUNDGREN.
